UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL MACHINE.

Application filed February 28, 1920, Serial No. 362,014. Renewed May 19, 1922. Serial No. 562,265.

To all whom it may concern:

Be it known that I, ERASTUS E. WINKLEY, a citizen of the United States, residing at Lynn, in the county of Essex and State of Massachusetts, have invented certain new and useful Improvements in Heel Machines; and I do hereby declare the following to be a full, clear, and exact description of the invention, such as will enable others skilled 10 in the art to which it appertains to make and use the same.

This invention relates to a machine for automatically producing heels for use in the manufacture of shoes, and more particularly 15 to a machine in which freshly pasted heels are introduced into a press in which they are held under comparatively light pressure during the setting or drying of the paste, and are thereafter transferred to a compressor in 20 which they are molded into shape under heavy pressure.

The general object of the invention is to provide a machine of the above named character which is simple in construction 25 and which will operate uniformly to produce a superior grade of heels.

To this end the present invention resides in a machine having pressing and compressing mechanisms and means for transferring 30 heels from the pressing mechanism to the compressing mechanism, said mechanisms and transferring means being arranged to cooperate as a unitary, single cycle machine, the operations of which are initiated by 35 means under the control of the operator and automatically arrested, at the end of each cycle, with the compressing instrumentalities closed to hold a heel under compression.

In the preferred embodiment of the 40 present invention, the pressing and compressing mechanisms are independently driven and each is loosely connected with its source of power by means of a driving belt. These mechanisms are, however, interconnected 45 and controlled in such a manner that they are constrained to operate in timed relation with each other. The operation of the pressing mechanism is initiated by, or in connection with, the act of introducing a heel 50 to said mechanism and is automatically arrested upon the completion of a single cycle of operations. The pressing mechanism, upon starting its cycle of operations, sets

the compressing mechanism in operation, the latter also performing one cycle of operations and then being automatically brought to rest. It is also preferred to control the transferral of the heels from the pressing mechanism to the compressing mechanism by the operation of the compressing mechanism but this arrangement is not, however, essential to the broader features of the invention.

The various features of the invention will be best understood from the description of 63 the preferred embodiment thereof illustrated in the accompanying drawings, in which:

Figure 1 is a top plan view of the machine; Fig. 2 is a view in rear elevation, on 70 an enlarged scale, showing the heel compressing mechanism together with feed mechanism for advancing a conveyor by means of which the heels are transferred from the pressing mechanism to the compressing mechanism; Fig. 3 is a top plan view, on an enlarged scale, of a portion of the heel-pressing mechanism, showing particularly a device for transferring the heels 75 from the pressing mechanism to the conveyor; Fig. 4 is a view, in front elevation, of certain of the parts shown in Fig. 3, the transferring device being shown in a different position and a portion of the frame 80 work of the machine being broken away to illustrate the construction more clearly; Fig. 5 is a detail sectional view, on an enlarged scale, taken on the line 5—5 of Fig. 1; Fig. 6 is a detail view, in front elevation, and on 85 an enlarged scale, showing a portion of the means for starting and stopping the heel-pressing mechanism; Fig. 7 is a detail view, 90 in side elevation, of a portion of the mechanism shown in Fig. 2, looking from right to left; Fig. 8 is a detail plan view 95 showing the mechanism for starting the operation of the heel-compressing mechanism; and Fig. 9 is a detail view, in side elevation, of a portion of the mechanism shown in Fig. 6.

Referring to Fig. 1 of the drawings, the machine constituting the present invention comprises, in general, a heel-press 10; a heel-compressor 12; a conveyor 14 by means of which the heels are carried from the press to the compressor; a transfferer 16, for re-

moving the heels singly from the press and depositing them on the conveyer; and a transerrer 18, for removing the heels singly from the conveyer and delivering them to the compressor.

Except for the details of construction and operation of the ejecting mechanism, the heel-press 10 is like that disclosed in applicant's Letters Patent of the United States No. 1,452,671, dated April 24, 1923, and assigned to the United Shoe Machinery Corporation, and therefore only a brief and general description of the common features of the machine will be given, reference being had to said patent for a more detailed description, if desired.

The heel-press 10 comprises an annular rotary carrier 20 which turns in a horizontal plane and supports a series of unit heel-clamps 22 having relatively movable, upper and lower, substantially horizontal, heel engaging members or jaws 24, the parts being so arranged that heels may be introduced to and from the clamps by movements in a horizontal plane. The rotary carrier 20 is moved intermittently, in the same direction, to bring the clamps 22 successively to a station 26 where the clamps are opened and the heels discharged therefrom. After the discharge of the heel from a clamp at the station 26, a fresh heel is loaded into the open clamp which closes upon the heel before the carrier starts its next feed movement. The intermittent feed movement of the carrier is effected by a suitable cam on a cam-sleeve 28, the sleeve being intermittently rotated by clutch mechanism 30 that is driven from a continuously operated power shaft 32. By means of the clutch mechanism 30 the press is caused to perform a single cycle of operations after which it is automatically arrested until again thrown into operation under the control of the operator.

The loading of the press is affected by a manually controlled spring-actuated feed-arm 34 (Fig. 3) which is adapted to swing horizontally across a feed-table 35 toward and from the loading and discharging station 26. The operator places a previously pasted rough heel, which is to be loaded into the press, between a pair of gage-members 36 that are carried by the feed-arm. The feed-arm is normally positioned and latched at one side of the feed-table 35, as shown in Figs. 1 and 3, and when a heel is placed between the gage-members 36 the heel is temporarily supported by a trip-plate 38 which controls the operation of the feed-arm. By exerting a slight downward pressure on the heel, after it has been placed between the gage-members 36, the operator causes the trip-plate to be depressed, whereupon the feed-arm is released and swings inwardly, carrying the heel into

an empty clamp at the station 26, the movement of the heel being limited by a breast-gage 40.

As so far described, the operation of the parts is the same as described in said Patent No. 1,452,671, above referred to. In the machine of said Patent, however, the breast-gage operates, just prior to the loading of a heel into a clamp of the rotary carrier, to eject from the clamp the heel which had been previously inserted therein and which has been held thereby a sufficient time for the setting or drying of the paste. In the present machine, however, inasmuch as the transerrer 16 is provided for removing the heels from the clamps 22, it is not necessary for the breast-gage 40 to perform also the function of an ejector. Accordingly, while the same provision is made, in the present as in the prior machine, for retracting the breast-gage 40, prior to each rotation of the clamp-carrier, the breast-gage is thereafter moved slowly toward the clamp, advancing slightly beyond normal position to dislodge the heel, in case it should be stuck in the clamp, and immediately being returned to its normal breast gaging position.

The compressor 12 (Figs. 1 and 2) is of a well-known type and, with the exception of its driving mechanism and its starting and stopping mechanism, is similar in its general characteristics to the machine disclosed in United States Letters Patent No. 1,213,052, granted January 16, 1917, to the present applicant, and assigned to the United Shoe Machinery Corporation. The construction and operation of the compressor need not therefore be described in detail. It should be understood, however, that the compressor is provided with the usual heel-compressing instrumentalities comprising a stationary heel-seat die, which is not shown in the drawings, but which is supported on the upper portion of a frame 42, and the usual heel mold (not-shown) which is carried by a vertically reciprocating cross-head 44, and is adapted to cooperate with the die to compress and shape a heel. Secured to the cross-head 44 and reciprocated therewith is a feed-table 46 which is provided with the usual side-guides 48 upon which the usual feed-slide 50 reciprocates horizontally for the purpose of feeding heels into position to be operated upon.

The mechanism for driving the compressor is similar to that disclosed in United States Letters Patent, No. 776,875, granted December 6, 1904, to E. A. Tripp, and assigned to the United Shoe Machinery Corporation. As therein illustrated and described, the compressor is adapted to be driven from a driving shaft 52 (Fig. 1) which is mounted in bearings in the rear portion of the supporting frame and is provided with fast and loose pulleys 54 and 56 respectively.

The driving shaft 52 is connected through suitable gearing with a crank-shaft 58 and a link 60 operatively connects the crank-shaft with an operating toggle (not shown) by 5 means of which the cross-head 44 is reciprocated.

The starting and stopping of the compressor is effected by shifting a driving belt into or out of engagement with the fast 10 pulley 54. The means for shifting the driving belt, as also shown in the above mentioned Tripp patent, comprises a belt-shifter 62 which slides in a bearing 64 at the rear of the frame 42 of the compressor. The 15 belt-shifter 62 is actuated by an arm 66 which is secured to a rock-shaft 68 that is journaled in bearings in the frame 42. In the patent referred to, the rock-shaft, corresponding to the shaft 68, is actuated by 20 means of a foot-treadle that is secured thereto. In the present construction, in lieu of a foot-treadle, an arm 70 (Figs. 6 and 9) is employed, the arm being secured to the rock-shaft 68 and acted upon by a suitable spring 25 72 which tends to raise the arm 70 and maintain the driving belt in engagement with the loose pulley 52. Provision is also made for automatically depressing and raising the arm 70 to control the starting and stopping of 30 the compressor.

The means for thus automatically controlling the starting and stopping of the compressor constitutes a feature of the present invention and comprises a lever 74 (Figs. 35 6 and 9) which is fulcrumed at one end on a stud 76 carried by the compressor frame 42. At its opposite end the lever 74 is provided with a spring pressed plunger 77 which bears against the upper longitudinal edge of the arm 70. The lever 74 is adapted to be actuated by means of a toggle comprising members 78 and 80. The toggle member 78 is pivoted at 82 to the lever 74 and the toggle member 80 is pivoted on a 40 stud 84 carried by a bracket that is secured to the compressor frame 42. The two toggle members are connected together by means of a knuckle pivot stud 86.

In order that the toggle 78-80 may be operated periodically by the heel-press, the knuckle pivot stud 86 is connected by means of a rod 88 with one arm of a cam lever 90 (Fig. 8) which is fulcrumed in a bracket 92 projecting from the frame of the press. 45 The other arm of the cam lever 90 carries a cam roll 94 which rides against the inner lateral face of a cam 96 which is secured to the cam-sleeve 28 of the press 10.

Shortly after the press 10 has started its 50 cycle of operations, the turning of the cam 96 causes the toggle 78-80 to be straightened and the lever 74 to be swung downwardly. As the lever 74 and the plunger 77 move downwardly, the arm 70 is depressed, thus 55 rocking the shaft 68 and throwing the belt-

shifter 62 to start the compressor. The shifting of the driving belt is completed just before the toggle becomes fully straightened and thereafter the spring pressed plunger 77 yields upwardly to permit 70 the additional downward movement of the lever 74 caused by the swinging of the knuckle pivot 86 to dead center. The cam 96 causes the knuckle pivot of the toggle to be carried just beyond dead center, whereupon the edge of the toggle link 78 engages a flat face 98 on the lever 74 which prevents further movement, toward the left in Fig. 6, of said pivot, so that the arm 70 is held depressed and the driving belt is maintained 75 in driving engagement with the fast pulley of the compressor.

The conveyer 14 by means of which the heels are carried from the press to the compressor, comprises an endless chain such, for example, as that shown in the applicant's Patent No. 1,213,052, hereinbefore mentioned. The conveyer chain extends from the press to the compressor and is supported 80 by two sprocket wheels 100 and 102, each consisting of a pair of notched disks which are fixed side-by-side on a common axle. The axle of the sprocket wheel 100 (Figs. 3 and 4) is journaled in a bearing bracket 103 that is secured to the frame of the press and the axle of the sprocket wheel 102 (Figs. 2 and 7) is journaled in suitable bearings supported by the frame 42 of the compressor. 85

The conveyer chain, as described in the aforesaid patent, comprises a series of flat links 104 which are pivoted together end-to-end by transverse pivot rods 105, the pivot rods extending through lateral flanges 106 which project downwardly from the links. Each link 104 is provided with a transverse rib 108 which engages the breast edge of the heel. At each side of the conveyer chain the pivot rods 105 are provided 95 with rollers 110 which are received in the notches in the sprocket wheels. 100

In the present machine it is desirable that the link of the conveyer chain which is in position to receive a heel from the trans- 105 ferrer 16 and the link from which a heel is to be removed by the transerrer 18 shall be supported in a horizontal plane. Inasmuch as the delivery end of the conveyer which is adjacent the compressor is higher than the receiving end thereof which is adjacent the press it is necessary to provide means for guiding the links horizontally as they leave the sprocket wheel 100 and as they approach the sprocket wheel 102. To this end a pair 110 of guide members 112 (Figs. 1, 3 and 4) are secured to the bearing bracket 103, and a pair of guide members 114 (Figs. 1 and 2) are secured to a portion of the frame 42 of the compressor, and these members are adapted to engage the rollers 110 so as to 115 120 125 130

maintain the links in the conveyer chain horizontal while they are adjacent the guide members.

The conveyer 14 is actuated step-by-step, 5 be feed mechanism which is associated with the compressor and derives its power from the reciprocations of the cross-head 44 and feed-table 46. This feed mechanism, which is a feature of the present invention, acts 10 during the operation of the compressor, while the cross-head 44 is rising, to advance the conveyer chain through the space of one link.

As shown in Figs. 2 and 7, the mechanism 15 for advancing the conveyer 14 comprises a ratchet wheel 116 which is secured to the axle of the sprocket wheel 102, and which is adapted to be rotated by a feeding pawl 118. The pawl 118 is carried by an arm 120 which is pivotally mounted on the axle of 20 the sprocket wheel 102, and a suitable spring is provided for holding the pawl against the ratchet wheel. In order that the pawl-carrying arm 120 may be oscillated to effect the feeding of the conveyer chain, said arm 25 is connected by a link 122 with the bent upper arm of a lever 124 that is pivotally mounted on a bracket 126 on the frame of the compressor. The lower arm of the lever 124 carries a roll 128 which is received in a cam 30 slot 130 that is formed in a plate 132 depending from the feed-table 46.

Upon the upward movement of the cross-head 44 and feed-table 46, one side of the 35 cam slot 130 causes the lever 124 to be rocked so that the feed pawl 118 will rotate the ratchet wheel 116 through the space of one tooth and advance the conveyer chain through the space of one link. Upon the 40 descent of the feed-table 46 the opposite side of the cam slot 130 causes the lever 124 to be rocked in the opposite direction so that the feed pawl 118 is retracted idly over one tooth of the ratchet wheel preparatory to its next feed movement.

In order to insure against accidental advancement of the conveyer during its periods of rest provision is made for locking the conveyer chain after each feed movement thereof. To this end a second ratchet wheel 50 134 is secured to the axle of the sprocket wheel 102 alongside of the ratchet wheel 116, the teeth of the ratchet wheel 134 being pitched oppositely to those of the ratchet wheel 116. The ratchet wheel 134 is engaged 55 by a locking pawl 136 which is pivoted on a fixed stud 138 and is normally held in locking position by a spring 140, one end of the spring being secured to a fixed part of the frame and its opposite end being secured 60 to a tail 142 on the locking pawl.

It is necessary to disengage the locking pawl from the ratchet wheel 134 prior to each feed movement of the feeding pawl 118 to permit the advance of the conveyer 65 chain. To this end the tail 142 of the lock-

ing pawl is engaged by the upper end of a trip-bar 144 having its lower end pivoted to one arm of a bell-crank lever 146 that is pivoted at 148 to the bracket 126. The other arm of the bell-crank lever 146 carries a 70 roll 150 which is received in a cam slot 152 in the plate 132 of the feed-table 46. The trip-bar 144 is normally maintained in operative engagement with the tail of the locking pawl by a spring 154, one end of which 75 is secured to the trip-bar while its opposite end is secured to a bracket 156 on the frame of the compressor.

As the feed-table of the compressor rises, 80 the trip-bar 144 is elevated sufficiently to disengage the locking pawl 136 from the ratchet wheel 134. Continued upward movement of the trip-bar 144 causes a cam face 158 (Fig. 2) which is formed upon the trip-bar to ride over the adjacent edge of the 85 bracket 156, thus swinging the upper end of the trip-bar outwardly from beneath the tail of the locking pawl and permitting the pawl to return into engagement with its ratchet wheel 134, so as to lock the conveyer 90 against further forward movement after the feeding pawl 118 has ceased to act. As the feed-table descends, the trip-bar 144 is reset so that it is ready to function again at the 95 next operation of the compressor.

The transerrer 16, by means of which the 100 heels are transferred from the clamps of the heel-press to the conveyer 14, comprises an arm 162 (Figs. 3 and 4) which is pivoted for horizontal swinging movement on a post 164 rising from the feed table 35 of the heel-press. The arm 162 carries a pair of clamp arms 166 between which the heels are gripped. In order that the transerrer arm 162 105 may be swung toward and from the press, a rearward extension 168 of the arm is connected by means of a rod 170 to one arm of a cam lever 172 (Fig. 5) which is fulcrumed on a stud 174 projecting from a portion of the frame of the compressor. The other arm 110 of the cam lever 172 carries a cam roll 176 which is received in a groove in a cam 178 that is secured to the crank shaft 58 of the compressor. The clamp arms 166 are pivotally mounted on the underside of the transerrer arm 162 and at the outer ends of the clamp arms are severally pivoted clamp plates 180, which are adapted to engage the 115 opposite curved edges of a heel.

In order that the clamp arms 166 may be 120 moved simultaneously toward and from each other so as to cause the clamp plates 180 to grip or release the heel, the arms 166 are connected by means of intermeshing segmental gears 182. The inward or clamping movement of the arms 166 is effected by a spring 184 which extends from one of said arms to the other. The clamp plates 180 are curved to conform to the curved contour 125 of the lateral edges of the heel and by reason 130

of their pivotal connection with the clamp arms 166 are permitted to readily adjust themselves to the heel.

Normally the clamp arms 166 are maintained in their inoperative or open position, as shown in Fig. 3, by means of a dog 186 which is pivoted on the underside of the transfer arm 162 and is provided with a shoulder 188 that engages an extension 190 of the inner clamp arm 166. A spring 192 holds the dog 186 in operative position.

When the transfer arm 162, as it swings toward the heel-press, approaches the end of its movement, a lug 194 on the dog 186 is engaged by a trip-pin 196 depending from a horizontal bracket 198 that is secured to the top of the post 164, the pin causing the dog to swing out from behind the extension 190 of the clamp arm and permit the spring 184 to swing the clamp arms toward each other, thus causing the clamp plates 180 to seize the heel preparatory to removing it from the open clamp of the heel-press. At the beginning of operations, before the rotary carrier of the heel-press has made a complete revolution, there will be no heels in the heel clamps of the carrier to be removed by the transfer 16. In the absence of a heel in the clamp of the carrier at the discharge station 26 when the transfer 16 swings inwardly, the closing movement of the clamp arms 166 of the transfer will be limited by the engagement of the extension 190 with a portion of the lug 194.

After seizing a heel the transfer arm 162 is swung away from the press, transferring the heel to the position indicated at 200, in Fig. 3, directly above an empty link of the conveyer chain which was advanced into position to receive the heel at the last feed movement of the conveyer. Just as the heel reaches this position, a pin 202 rising from the inner segmental lever 182, engages a lug 204 depending from the bracket 198, and the clamp arms 166 are caused to swing outwardly to release the heel which is deposited, base lift end down, on the empty conveyer link in the position shown in Fig. 3, with its breast adjacent the transverse rib 108 of said link and disposed at right angles to the position it occupied in the press. As the clamp arms swing outwardly, the clamp arm extension 190 passes beyond the shoulder 188 on the dog 186 and the dog moves inwardly bringing the shoulder 188 behind the extension 190, thus locking the clamp arms in open position.

Each step movement of the conveyer advances a heel into position to be transferred to the feed slide 50 of the compressor. The transfer 18, by means of which the transfer from the conveyer to the compressor is effected, is the same in construction and arrangement as the corresponding device illustrated and described in applicant's Let-

ters Patent No. 1,213,052, hereinbefore referred to.

As set forth in said patent, the transfer 18 comprises a pair of clamping jaws 208, which are carried by a clamp body 210 that is mounted on the frame of the compressor. The clamping jaws 208 are operated to seize a heel by engagement with its opposite lateral surfaces and the clamp body 210 is rocked by the upward movement of the cross-head and feed-table about a horizontal axis parallel to the direction of feed of the conveyer, swinging the heel through an arc of 180° and thus inverting it and bringing it into position to be deposited upon the feed-slide of the compressor. The clamping jaws 208 are then operated to release the heel which is deposited, top lift end down, on the feed-slide.

In the present machine the transfer 18 swings toward the conveyer, during the first part of the cycle of operations of the compressor, and seizes the heel carried at the leading end of the conveyer. During the latter part of the cycle of operations of the compressor, the heel is deposited by the transfer 18 upon the feed-slide of the compressor and then the conveyer is advanced, by the feed mechanism hereinbefore described, to bring another heel into position for transferral to the compressor at the next cycle of operations. The compressor is then automatically stopped and is not started again until a new heel has been inserted in the heel-press.

Heel compressors, heretofore employed, have been constructed and arranged to operate continuously and accordingly the heels were subjected to compression only while the cross-head of the compressor was momentarily in its uppermost position. In the present machine, a certain period of time necessarily elapses between successive cycles of operation of the compressor, before a fresh heel has been introduced into the press and the cam 96 has operated to again start the compressor and, in order to increase the effectiveness of the compressor the arrangement is such that the operation of the compressor is arrested when the cross-head is in its uppermost position, so that the heel is maintained under compression in the mold during the interval when the compressor is at rest. By thus keeping the heels under compression in the mold for an appreciable length of time instead of only momentarily, as heretofore, more smoothly finished and more thoroughly compressed heels are produced.

The compressor is automatically stopped after each cycle of operations by cam-actuated mechanism which breaks the toggle 78-80 and permits the spring 72 to raise the arm 70 and rock the shaft 68 in a direction to shift the driving belt from the fast

pulley 54 to the loose pulley 56. In the construction shown, a bell-crank lever 214 (Fig. 5) is fulcrumed on the stud 174, alongside the lever 172, and carries at the end of its upper arm a cam roll 216 which rides on the periphery of the cam 178. The lever 214 is actuated by a projecting portion 218 on the periphery of the cam 178. The lower arm of the lever 214 is connected by a rod 220 with an arm 222 (Fig. 6) which is secured to a rock shaft 224 that is journaled in bearings on the frame of the compressor. Extending downwardly from the rock shaft 224 is a trip-arm 226 which is adapted to engage a dog 228 that is pivoted, intermediate its upper and lower extremities, upon an upward extension of the toggle link 80 and is normally held by a spring 230 with its lower end against a shoulder 232 on the extension of the toggle link 80. At each cycle of operations of the machine, after the toggle formed by the members 78 and 80 is straightened, to start the operation of the compressor, the trip-bar 226 first swings in a counter-clockwise direction, viewing Fig. 6, and the dog 228, when engaged by the trip-arm, rocks idly against the tension of the spring 230, permitting the trip-arm to pass beyond the dog. The dog 228 is then restored by its spring 230 to its normal position against the shoulder 232. Upon the movement of the trip-arm in the opposite direction, however, just before the compressor is automatically brought to rest, the dog 228 is prevented from rocking about its pivot by the shoulder 232 and as a result the toggle link 80 is swung by the trip-arm in a direction to break the toggle 78-80 and cause the shaft 68 to be rocked so as to effect the shifting of the belt from the fast pulley of the compressor to the loose pulley. The compressor is then brought to rest with the compressing instrumentalities closed to hold a heel under compression.

The operation of the machine is as follows: Assuming that the heel-press and the conveyer 14 are filled to capacity with rough heels, the operator places a previously pasted rough heel between the gage members 36 of the feed-arm 34 and depresses the heel slightly to operate the trip-plate 38. The feed-arm then swings inwardly toward the heel-press, introduces the heel into an empty heel clamp which is open and ready to receive it at the receiving and discharging station 26, and immediately returns to its normal retracted position. The inward movement of the feed-arm automatically starts the operation of the press, rotating the clamp carrier 20 one step, in the direction of the arrow in Fig. 1, thereby advancing the next heel clamp into position to discharge its heel and receive a new heel. The step movement of the clamp carrier operates in the manner hereinbefore described to

start the operation of the compressor which is normally at rest with the cross-head in its uppermost position holding a heel under pressure in the mold. As the compressor starts to operate, the cross-head 44 and feed-table 46 descend, and at the same time the feed-slide 50 advances toward the heel mold in the cross-head, carrying a rough heel which was deposited thereon at the preceding cycle of operations. The transferrer 18, which was positioned with its clamping jaws 208 extending over the feed-slide 50, swings toward the conveyer and the jaws 208 close upon the heel that is carried at the leading end of the conveyer. At the end of the downward movement of the cross-head 44 the heel, which was compressed at the preceding cycle of operations of the compressor, is ejected by the feed-slide from the mold and the rough heel carried by the feed-slide is deposited in the mold. The cross-head and feed-table then rise, the feed-slide being simultaneously retracted from the mold. On the upward movement of the cross-head and the feed-table the transferrer 18 starts to swing toward the feed-table. The conveyer is then unlocked and advanced through the space of one link, bringing another heel into position to be seized, at the next cycle of operations, by the clamping jaws of the transferrer 18, and advancing an empty link into position to receive a heel from the press before the completion of the present cycle. As the cross-head reaches its uppermost position, it comes into cooperative relation with the heel-seat die compressing the heel in the mold. The feed-slide is then in its fully retracted position and the heel carried by the transferrer 18 is deposited thereon. During the last part of the cycle of operations of the compressor and just after the advance of the conveyer chain, the transferrer 16 is swung toward the press and seizes the heel, which is in the open clamp at the station 26, and immediately returns and deposits the heel upon the empty link of the conveyer chain. The trip-arm 226 is then actuated to break the toggle, comprising the members 78 and 80, and the compressor is automatically stopped with the cross-head in its uppermost position, holding a heel under compression in the mold. The operator then places another previously pasted rough heel between the gage members of the feed-arm 34 and depresses the heel, thus causing the feed-arm to swing inwardly, as before, introducing another heel into the press and initiating another cycle of operations of the machine.

From the foregoing description it will be apparent that while the pressing and the compressing mechanisms of the present machine are independently driven and loosely connected with a source of power, by means of driving belts which are liable to slip and

thus permit the two mechanisms to get out of step with each other, these mechanisms are, nevertheless so interconnected and controlled as to cooperate in definite timed relation as a unitary single cycle machine. The stopping of the compressor, at the completion of each successive cycle of operations, with the compressing instrumentalities closed upon the heel, insures the production of heels which are more smoothly finished and more thoroughly compressed than those produced by compressing mechanisms heretofore employed.

While the particulars of construction herein set forth are well suited to one form of the invention, it is to be understood that these particulars are not essential since they may be variously modified within the skill of the artisan without departing from the true scope of the actual invention as defined by the following claims.

Having described the invention, that which is claimed as new is:—

1. A machine for operating upon heels having, in combination, a heel moulding-compressor adapted to perform a single cycle of operations and automatically come to rest with the compressing instrumentalities closed to hold a heel under pressure, means for advancing simultaneously a series of heels to be delivered successively to the compressor and means for starting the operation of the compressor by the act of supplying a remote heel in said series to be operated upon.

2. A machine for operating upon heels having, in combination, a single cycle heel-press, a single cycle heel moulding-compressor, means for transferring a series of heels in unison from the press to the compressor, and means under the control of the operator and dependent upon the supplying of a heel to the end of said series for initiating each cycle of operations of the press and the compressor.

3. A machine for operating upon heels having, in combination, a heel-compressor having its compressing instrumentalities normally closed, means for initiating the operation of the compressor, ejecting the previously compressed heel and supplying a fresh heel thereto, and means for automatically arresting the operation of the compressor with the compressing instrumentalities closed to hold the fresh heel under compression.

4. A machine for operating upon heels having, in combination, a heel-press for holding freshly pasted heels under comparatively light pressure during the setting of the paste, and means dependent upon the operation of the press for removing the heels from the press and compressing them in a mold under heavy pressure.

5. A machine for operating upon heels

having, in combination, a heel-press for holding freshly pasted heels during the setting of the paste, a heel moulding-compressor controlled by the operation of the press, and means for transferring the heels from the press to the compressor.

6. A machine for operating upon heels having, in combination, a heel-press, a heel moulding-compressor controlled by the operation of the press, and means controlled by the operation of the compressor for transferring heels from the press to the compressor.

7. A machine for operating upon heels having, in combination, a heel-press, a heel-compressor, a conveyer extending from the press to the compressor, means for transferring heels from the press to the conveyer, and means for transferring heels from the conveyer to the compressor.

8. A machine for operating upon heels having, in combination, a heel-press, a heel-compressor, a conveyer extending from the press to the compressor, and means controlled by the operation of the compressor for transferring heels from the press to the conveyer and from the conveyer to the compressor.

9. A machine for operating upon heels having, in combination, a heel-press, a heel-compressor controlled by the operation of the heel-press, a conveyor extending from the press to the compressor, means for transferring heels from the press to the conveyor, and means for transferring heels from the conveyor to the compressor.

10. A machine for operating upon heels having, in combination, a heel-press, a heel-compressor controlled by the operation of the heel-press, a conveyer extending from the press to the compressor, and means controlled by the operation of the compressor for transferring heels from the press to the conveyer and for transferring heels from the conveyer to the compressor.

11. A machine for operating upon heels having, in combination, a rotatable heel-press adapted to advance through a series of step-movements to bring heels successively to a discharging station, a compressor, and means for transferring the heels from the press to the compressor.

12. A machine for operating upon heels having, in combination, a rotatable heel-press adapted to advance through a series of step-movements to bring heels successively to a discharging station, a conveyer for receiving the heels as they are discharged from the press, and a compressor adapted to receive the heels from the conveyer.

13. A machine for operating upon heels having, in combination, a rotatable heel-press adapted to advance through a series of step-movements to bring heels successively to a discharging station, a heel-com-

pressor adapted to perform one cycle of operations and automatically come to rest, means for transferring the heels from the press to the compressor, and means rendered operative by the stepping of the press for initiating the operation of the compressor.

14. A machine for operating upon heels having, in combination, a heel-press provided with a series of heel-clamps, means for 10 intermittently advancing said clamps to bring them successively to a discharging station, a heel-compressor adapted to perform one cycle of operations and automatically come to rest, means rendered operative by the stepping of the press for initiating the operation of the compressor, and means controlled by the operation of the compressor for transferring heels from the press to the compressor.

15. A machine for operating upon heels having, in combination, a heel-press provided with a series of heel-clamping units each adapted to clamp a freshly pasted heel to hold it during the setting of the paste 25 and subsequently release it to permit its removal from the press, a heel-compressor, means arranged to transfer the heels from the heel-clamping units to the compressor, and means arranged to move the heel-clamping units successively into registry with the transferring means.

16. A machine for operating upon heels having, in combination, a rotatable heel-press adapted to advance through a series 35 of step-movements to bring heels successively to a discharging station, a heel-compressor adapted to be rendered operative by the stepping of the press and to perform one cycle of operations and automatically come 40 to rest with a heel held under pressure therein, and means for transferring the heels from the press to the compressor.

17. A machine for operating upon heels having, in combination, a heel-press provided with heel-clamping units adapted to be opened and closed, a heel-compressor controlled by the press, a conveyer for carrying heels to the compressor, and a transfer controlled by the compressor for 50 seizing a heel in an open clamp of the press and depositing the heel upon the conveyer.

18. A machine having, in combination, two independently driven mechanisms loosely connected with their source of power for 55 performing successive operations upon articles, a conveyer controlled by one of the mechanisms for carrying the articles operated upon from the first mechanism to the second mechanism, in a series of steps, 60 means for controlling the operation of the second mechanism by the first mechanism to secure proper time relation of the two mechanisms with each other and with the conveyer, and a transfer device controlled by the second mechanism for transferring 65

articles from the first mechanism to the conveyer in proper time relation to the advance of the conveyer.

19. A machine for operating upon heels having, in combination, a heel-press and a 70 heel-compressor for performing successive operations upon heels, said press and compressor being independently driven and loosely connected with a source of power, a conveyer controlled by the compressor for 75 carrying the heels from the press to the compressor in a series of step movements, means for controlling the operation of the compressor by the press to secure proper 80 time relation of the conveyer and the compressor with the press, and transfer mechanism controlled by the compressor for transferring the heels from the press to the conveyer in proper time relation to the advance of the conveyer.

20. A machine for operating upon heels having, in combination, a heel-press, a heel-compressor having a reciprocating cross-head, the press and compressor being independently driven and loosely connected 90 with a source of power and adapted to operate successively upon heels, a conveyer operated in steps by the reciprocations of the cross-head of the compressor, for carrying heels from the press to the compressor, 95 means for controlling the operation of the compressor by the press to secure proper time relation of the conveyer and compressor with the press, and transfer mechanism for transferring the heels from the press to the conveyor in proper time relation to the advance of the conveyer.

21. A machine for operating upon heels having, in combination, heel-molding instrumentalities normally held in compressing 100 relation, means for actuating said instrumentalities during the operation of the machine, means for advancing step-by-step a series of heels to be molded and for periodically supplying said heel-molding instrumentalities with a single heel, and means 105 for arresting the operation of the machine with the heel-molding instrumentalities closed to hold the first heel of said series under pressure.

22. A machine for operating upon heels and adapted to perform a single cycle of operations and come to rest having, in combination, normally closed heel-molding instrumentalities, means for actuating said instrumentalities during the operation of the machine, means for advancing step-by-step a series of heels to be molded and for periodically supplying said heel-molding instrumentalities with a single heel, automatic means for arresting the operation of the machine with the heel-molding instrumentalities closed to hold the first heel of said series under pressure, and means for starting the operation of the ma- 125 130

chine by the act of supplying an additional heel to said series.

23. A machine for operating upon heels having, in combination, a heel-press, a heel-molding compressor, means for transferring a series of heels from the press to the compressor, and means dependent upon the supplying of a heel to the press for addition to said series for starting the press and compressor into operation.

24. A machine for operating upon heels having, in combination, a heel-press, means for initiating the operation thereof, a heel-compressor, means for transferring heels from the press to the compressor, and means dependent upon the operation of the press for initiating the operation of the compressor.

25. A machine for operating upon heels having, in combination, a single cycle heel-press, means for initiating the operation thereof, a single cycle heel-compressor, means for transferring heels from the press to the compressor, and means dependent upon the operation of the press for starting the compressor into operation in time relation therewith.

26. A machine for operating upon heels having, in combination, a single cycle heel-press, means for initiating the operation thereof, a single cycle heel-compressor, and means dependent upon the operation of said press for starting the compressor into operation and transferring heels from the press to the compressor.

27. A machine for operating upon heels having, in combination, a heel-press, a heel-compressor adapted to operate in time relation therewith, means for seizing and removing heels from the heel-press, and means actuated by said heel compressor for transferring said heels from the press to the compressor.

28. A machine for operating upon heels having, in combination, a heel-press for holding freshly pasted heels under pressure until the paste has set and for periodically effecting the release of a heel, a heel-compressor rendered operative by the operation of the press and constructed and arranged to perform a single cycle of operations and automatically come to rest with the heel held under pressure therein, and means for transferring the released heels from the press to the compressor.

29. A machine for operating upon heels having, in combination, a single cycle heel-press for holding a plurality of heels under pressure, a single cycle heel-molding compressor constructed and arranged to automatically come to rest with a single heel held under molding pressure therein, and means for automatically transferring a heel from the press to the compressor and for supplying the press with a new heel.

30. A machine having, in combination, two mechanisms independently driven from their source of power for performing successive operations upon articles, a conveyer controlled by one of the mechanisms for carrying articles from the first mechanism to the second mechanism, means for controlling the operation of the second mechanism by the first mechanism to secure the proper time relation of the two mechanisms with the conveyer, and means controlled by one of said mechanisms for transferring articles from the first mechanism to the conveyer in proper time relation to the advance of the conveyer.

31. A machine having, in combination, two mechanisms independently driven from their source of power for performing successive operations upon articles, means controlled by one of said mechanisms for transferring the articles from the first mechanism to the second mechanism, and means for controlling the operation of the second mechanism by the first mechanism to secure proper time relation of the two mechanisms with the transferring means.

32. A machine having, in combination, two mechanisms independently driven from their source of power for performing successive operations upon articles, means dependent upon the operation of the first mechanism for starting the second mechanism into operation in proper time relation, and means operated in time relation with said mechanisms for transferring articles from the first mechanism to the second mechanism.

33. A machine for operating upon heels having, in combination, a heel-press and a heel-compressor for performing successive operations upon heels, said press and compressor being independently driven from their source of power, means for controlling the operation of the compressor by the press to secure proper time relation of the press and compressor, and a conveyer operated in proper time relation with said press and compressor for transferring heels from said press to said compressor.

34. A heel machine having, in combination, heel pressing and heel compressing machines interconnected so as to be operated in time relation as a unitary machine, a conveyer for carrying heels from the press to the compressor, and means for seizing heels while in the press and delivering them to the conveyer, both the conveyer and delivering means being controlled by the compressor to secure proper time relation therewith.

35. A heel machine having, in combination, two mechanisms arranged in series for performing successive operations upon a heel, and means for transferring the heel from one mechanism to the other comprising

ing a clamping device movable in the intervening space for gripping the heel by its lateral surface, constructed and arranged to close automatically upon the heel and be positively opened to release the heel.

36. In a heel machine comprising two mechanisms arranged in series for performing successive operations on a heel, a transfer device for seizing a heel at the first machine and withdrawing it therefrom comprising a pair of spring pressed clamping arms for gripping the lateral surface of a heel and positively acting means to open said arms and release the heel, and means for moving said device toward and from said first machine.

37. In a machine of the type in which a cross-head is reciprocated at each cycle of operations and blanks are brought to a position for delivery to the machine by a movable conveyer, mechanism to advance said conveyer comprising a ratchet on the conveyer, a pawl for engaging said ratchet, a lever carrying said pawl movable to give said pawl effect, and connections between said lever and the movable cross-head of the machine operating to reciprocate said pawl once for each complete cycle of operations of the machine.

38. In a machine of the type in which a cross-head is reciprocated at each cycle of operations and blanks are brought to a position for delivery to the machine by a movable conveyer, means to advance said conveyer comprising co-operating feed devices on the conveyer and machine, and a cam carried by a moving part of the machine connected to operate said devices.

39. In a machine of the type in which a cross-head is reciprocated at each cycle of operations and blanks are brought to a position for delivery to the machine by a movable conveyer, mechanism for actuating said conveyer, and a cam on the cross-head of said machine co-operatively connected with said means in a manner to cause an advance of the conveyer at each operation of the machine.

40. In a machine of the type in which a cross-head is reciprocated at each cycle of operations and blanks are brought to a position for delivery to the machine by a movable conveyer, mechanism adapted to advance said conveyer step-by-step, including means connecting said mechanism with the cross-head of the machine whereby the conveyer advance is controlled by the operation of the machine.

41. In a machine of the type in which a cross-head is reciprocated at each cycle of operations and blanks are brought to a position for delivery to the machine by a mov-

able conveyer, mechanism to advance said conveyer step-by-step comprising a ratchet and co-operating feed and locking pawls, and means controlled by the reciprocation of the cross-head of said machine for rendering said pawls effective in proper time relation to each other.

42. In a machine of the type in which a cross-head is reciprocated at each cycle of operations and blanks are brought to a position for delivery to the machine by a movable conveyer, mechanism to advance said conveyer step-by-step comprising a ratchet and co-operating feed and locking pawls, levers for controlling the movement of said pawls into and out of engagement with said ratchet, and means controlled by the operation of the machine for actuating said levers.

43. In a machine of the type in which a cross-head is reciprocated at each cycle of operations and blanks are brought to a position for delivery to the machine by a movable conveyer, mechanism to advance said conveyer step-by-step comprising a ratchet and cooperating feed and locking pawls, an operating lever for each pawl provided with a cam roll, and cam means on the cross-head for actuating said levers by engagement with said rolls.

44. In a machine of the type in which a cross-head is reciprocated at each cycle of operations and blanks are brought to a position for delivery to the machine by a movable conveyer, mechanism for advancing said conveyer step-by-step controlled by the rise of said cross-head, and mechanism normally locking said conveyer against advance rendered ineffective by said rise of the cross-head.

45. In a machine of the type in which a cross-head is reciprocated at each cycle of operations and blanks are brought to a position for delivery to the machine by a movable conveyer, mechanism controlled by the operation of the machine to advance the conveyer step-by-step, and means to lock the conveyer against an advance movement during its periods of rest.

46. In a machine of the type in which a cross-head is reciprocated at each cycle of operations and blanks are brought to a position for delivery to the machine by a movable conveyer having an intermittent feed, means to lock the conveyer against an advance movement during its periods of rest, and mechanism controlled by the machine to release the lock and advance the conveyer one step at each cycle of operations of the machine.

ERASTUS E. WINKLEY.
